UNITED STATES PATENT OFFICE.

KARL KÜPFMÜLLER, OF BERLIN-FRIEDENAU, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

IMPEDANCE-CORRECTING NETWORK.

Application filed August 23, 1921, Serial No. 494,519, and in Germany September 10, 1919.

(GRANTED UNDER THE PROVISIONS OF THE ACT OF MARCH 3, 1921, 41 STAT. L., 1313.)

I have filed applications as follows: Germany September 10, 1919, Patent No. 330,964; Sweden September 2, 1920; Switzerland September 6, 1920; Italy September 10, 1920; 5 Norway September 10, 1920.

The problem of simulating artificially the electric qualities of actual transmission lines occurs frequently in telephony and telegraphy. For instance, several reciprocal repeater connections in telephonic or telegraphic lines require the simulation of the impedance of the transmission line.

For the usual aerial lines the solution of this problem presents no difficulties. The 15 characteristic impedance W of such a line is given approximately by the formula

$$(1) \quad W = \sqrt{\frac{L}{C}} - i \frac{R}{2\omega\sqrt{LC}}.$$

20 In this formula L , C and R denote the kilometric values of the inductance, capacity and ohmic resistance of the line; $i = \sqrt{-1}$ and ω the frequency in cycles viz, the number of periods of the sinusoidal current within 2π sec.

25 In the drawing, Fig. 1 shows a network for matching the impedance of a homogeneous line; Fig. 2 shows the generalized network of this invention; Figs. 3 and 7 show two particular embodiments of the invention; Figs. 30 4, 5 and 6 show the simulation of the combined impedance of the network shown in Fig. 3 and a coil loaded line to the characteristic impedance of a homogeneous line for different values of K and C_1 , respectively; 35 and Fig. 6 shows the precision of simulation obtainable with the network Fig. 7.

As shown in Fig. 1 the characteristic impedance of such a line is simulated in a known manner by an ohmic resistance having the value $\sqrt{\frac{L}{C}}$ connected in series with a condenser of the capacity $\frac{2\sqrt{LC}}{R}$.

45 When however the impedance of a coil

loaded line is to be simulated the problem becomes difficult. The impedance of such a line depends in a rather complicated manner upon the frequency and therefore requires an arrangement much more complicated for 50 the simulation. An artificial line designed for this purpose has been indicated by R. S. Hoyt in the United States Patent No. 1,167, 693. For many purposes, however, the necessity of being dependent upon the frequency is 55 inconvenient.

The object of the invention hereinafter described is to avoid this dependency by transforming the electric qualities of the loaded lines in such a manner that their impedance becomes equal to that of a homogeneous aerial line, so that the simulation used for aerial lines may also be applied to loaded lines transformed according to the invention. 60

The formula for the mid load characteristic impedance of a loaded line (see K. W. Wagner, Archiv für Elektrotechnik, Band VIII, 1919, page 61 etc.) is

$$(2) \quad W = \sqrt{\frac{R_o + iL_o\omega}{i\omega C_o}} \cdot \frac{1}{\sqrt{1 + \frac{1}{4}iC_o\omega(R_o + iL_o\omega)}}, \quad 70$$

In this formula $R_o = s \cdot R + R_s$, $C_o = sC$, $L_o = s \cdot L + L_s$, where R_s and L_s denote the resistance respectively the inductance of the coil and s the length of the line between two coils. The influence of the capacity of the coil is so small that it may be neglected. 75

A mathematical simulation or close precision of the impedance is not necessary in practice. Divergences of 2% from the precise value are allowable. A simulation of greater precision would be of no avail, since in practice the real value differs about 2% from the theoretically calculated value of the characteristic impedance as a function of the frequency on account of structural inexactness in the construction of the lines and 80 85 90

the coils. These differences are sometimes positive and sometimes negative so that the formula for W (2) gives the mean value of the actual characteristic impedance.

5 Taking into consideration these relations the Equation 2 may be brought into a form

from which results the arrangement herein described. By a simple transformation and the substitution of the limiting frequency

ω_0 for $\sqrt{\frac{4}{L_o C_o}}$ results of the Equation 2 (see 10 K. W. Wagner above).

$$W = \sqrt{\frac{\frac{L_o}{C_o} + \frac{R_o}{i C_o \omega}}{1 - \left(\frac{\omega}{\omega_0}\right)^2 + \frac{i}{4} R_o C_o \omega}} = \sqrt{\frac{\frac{L_o}{C_o} \left(1 - \left(\frac{\omega}{\omega_0}\right)^2\right) - i \frac{R_o}{C_o \omega} \left(1 - \left(\frac{\omega}{\omega_0}\right)^2\right) - \frac{R_o^2}{4} - \frac{i}{4} R_o L_o \omega}{\left(1 - \left(\frac{\omega}{\omega_0}\right)^2\right)^2 + \frac{1}{16} R_o^2 C_o^2 \omega^2}}$$

This equation may be simplified in taking into consideration the known practical values of L_o , C_o and R_o for frequencies below

15 the limiting frequency that is to say for only those frequencies coming into consideration for the transmission. For the loaded cable leading from Berlin to the Rhineland (2mm. wire diameter) for instance the following values are to be considered

$$R_o = 27 \Omega; L_o = 0.24 \text{ henry}; \\ C_o = 0.065 \mu\text{F}.$$

From these values it results that in the denominator the term 25

$$\frac{1}{16} R_o^2 C_o^2 \omega^2$$

may be neglected as compared with the term

$$\left(1 - \left(\frac{\omega}{\omega_0}\right)^2\right)^2$$

up to near the limiting frequency. Then

$$W = \sqrt{\frac{\frac{L_o}{C_o} - \frac{R_o^2}{4 \left(1 - \left(\frac{\omega}{\omega_0}\right)^2\right)^2} - i \frac{R_o}{C_o \omega}}{\left(1 - \left(\frac{\omega}{\omega_0}\right)^2\right)^2}} = \sqrt{\frac{\frac{L_o}{C_o} - \frac{R_o^2}{4 \left(1 - \left(\frac{\omega}{\omega_0}\right)^2\right)}}{1 - \left(\frac{\omega}{\omega_0}\right)^2} - i \frac{R_o}{C_o \omega \left(1 - \left(\frac{\omega}{\omega_0}\right)^2\right)^2}}$$

For the terms of this equation the following 35 values given above and for the frequencies $\omega = 7000$ values are obtained in employing the practical values given above and for the frequencies $\omega = 7000$

$$\frac{L_o}{C_o} = 3.7 \cdot 10^6; \frac{R_o^2}{4 \left(1 - \left(\frac{\omega}{\omega_0}\right)^2\right)} = 226; \frac{R_o}{C_o \omega \left(1 - \left(\frac{\omega}{\omega_0}\right)^2\right)} = 7.3 \cdot 10^4.$$

Above all the term

$$\frac{R_o^2}{4 \left(1 - \left(\frac{\omega}{\omega_0}\right)^2\right)}$$

40 may be neglected compared with the term $\frac{L_o}{C_o}$ till near to the limiting frequency. Further the imaginary part amounts about to $1/50$ of the real part; since with regard to the simulation the vector W is of particular importance, the influence of the imaginary part which is directed approximately at right angles to the vector is therefore very small and the correspondence of the two sides of the equation is not materially influenced, by writing

$$55 \quad \frac{R_o}{C_o \omega} \approx \frac{\frac{R_o}{C_o \omega} + \frac{R_o L_o \omega}{4}}{1 - \left(\frac{\omega}{\omega_0}\right)^2},$$

that is to say when the approximate formula

$$60 \quad \frac{1}{1 - \left(\frac{\omega}{\omega_0}\right)^2} = 1 + \left(\frac{\omega}{\omega_0}\right)^2$$

65 is applied.

With regard to this

$$70 \quad W = \sqrt{\frac{1}{1 - \left(\frac{\omega}{\omega_0}\right)^2} \sqrt{\frac{L_o}{C_o} - i \left(\frac{R_o}{C_o \omega} + \frac{R_o L_o \omega}{4}\right)}}.$$

75 With the aid of the real relative values, the radical may be dissolved as follows:

$$\sqrt{m-n} \approx \sqrt{m} - \frac{n}{2\sqrt{m}},$$

$$(3) \quad W = \sqrt{\frac{L_0}{C_0}} \sqrt{\frac{1}{1 - \left(\frac{\omega}{\omega_0}\right)^2}} - i \frac{R_0}{4} \left(\frac{\omega}{\omega_0} + \frac{\omega_0}{\omega} \right) \sqrt{\frac{1}{1 - \left(\frac{\omega}{\omega_0}\right)^2}}.$$

For long distance lines the impedance U_1 is practically equal to the characteristic impedance. From the Equation 3 results

$$(4) \quad U_1 = \frac{a}{c} - i \frac{b}{c},$$

wherein

$$a = \sqrt{\frac{L_0}{C_0}}; \quad b = \frac{R_0}{4} \left(\frac{\omega}{\omega_0} + \frac{\omega_0}{\omega} \right); \quad c = \sqrt{1 - \left(\frac{\omega}{\omega_0} \right)^2}.$$

From the Equations 3 and 4 it results that the impedance of the coil loaded line varies in a very complicated manner with the frequency.

The present invention indicates an arrangement for compensating this undesired dependance of the simulation upon the frequency sufficiently, to make the simulation for the range of frequencies, below the particular value of the limiting frequency concerned in

$$(5) \quad U_0 = \frac{\frac{a}{c}}{\left(1 - \frac{b}{G_1 c}\right)^2 + \frac{a^2}{G_1^2 c^2}} + i \frac{\frac{a^2}{G_1 c^2} - \frac{b}{c} + \frac{b^2}{G_1 c^2}}{\left(1 - \frac{b}{G_1 c}\right)^2 + \frac{a^2}{G_1^2 c^2}} + i G_2.$$

The real constituent of the characteristic impedance of a homogeneous aerial line is independent of the frequency according to the Formula 1. If this shall also be true for U_0 , G_1 in the Equation (5) is to be chosen in such a manner that

$$(6) \quad \frac{1}{c} = \left(1 - \frac{b}{G_1 c}\right)^2 + \frac{a^2}{G_1^2 c^2}.$$

By this the Equation 5 is reduced to

$$50 \quad U_0 = a + i \left(\frac{a^2 + b^2}{G_1 c} + G_2 - \frac{R_0 \omega}{4 \omega_0} \right) - i \frac{R_0 \omega_0}{4 \omega}.$$

According to the Equation 1 the imaginary portion of the characteristic impedance of a homogeneous line is equal to the impedance of a condenser. In order to obtain this condition for U_0 , G_2 must correspond to the equation

$$60 \quad (7) \quad \frac{a^2 + b^2}{G_1 c} + G_2 - \frac{R_0 \omega}{4 \omega_0} = 0,$$

$$G_2 = \frac{R_0 \omega}{4 \omega_0} - \frac{a^2 + b^2}{G_1 c}.$$

Then remains only

$$65 \quad U_0 = a - i \frac{R_0 \omega_0}{4 \omega},$$

a given case, equal to the characteristic impedance. Further, by the present invention, the conditions are indicated according to which such an arrangement is to be dimensioned for a given line.

According to Fig. 2 an auxiliary device is inserted before the impedance U_1 . G_1' and G_2' are impedances composed of condensers and inductances provisionally arranged in any desired manner. The values of these impedances may be written in the form $i \cdot G_1$ and $i \cdot G_2$, wherein G_1 and G_2 indicate real numerical values. The resistance at the ends of the net formed in this manner is

$$35 \quad U_0 = \frac{U_1 i G_1}{U_1 + i G_1} + i G_2$$

From the substitution of the expression (4) for U_1 results

This value may be represented according to Fig. 1 by connecting in series an ohmic resistance

$$70 \quad a = \sqrt{\frac{L_0}{C_0}}$$

and a capacity

$$75 \quad C = \frac{4}{R_0 \omega_0}$$

A simple arrangement satisfying within a practical sufficiently large range the conditions 6 and 7 is obtained for instance by choosing for G_1' (Fig. 2) a capacity K and for G_2' a parallel resonant circuit and an inductance in series as shown in Fig. 3. When the values of these elements are chosen to fulfill the conditions (6) and (7) and the terminals of the network marked V_1 connected to a coil loaded line, the resulting impedance of the combination will be equal to the characteristic impedance of a homogeneous line. In the two Equations 6 and 7 are to be inserted

$$80 \quad G_1 = -\frac{1}{K \omega}; \quad G_2 = \frac{L_1 \omega}{1 - L_1 C_1 \omega^2} + L / \omega$$

From this results for the Equation 6

$$85 \quad (8) \quad \frac{1}{\sqrt{1 - \left(\frac{\omega}{\omega_0}\right)^2}} = \left(1 + \frac{K \omega \frac{R_0}{4} \left(\frac{\omega}{\omega_0} + \frac{\omega_0}{\omega} \right)}{\sqrt{1 - \left(\frac{\omega}{\omega_0}\right)^2}} \right)^2 + \frac{L_0 K^2 \omega^2}{C_0 \left(1 - \left(\frac{\omega}{\omega_0} \right)^2 \right)}.$$

For obtaining K from this equation, we may provisionally write

$$5 \quad (9) \quad \frac{1}{\sqrt{1 - \left(\frac{\omega}{\omega_0}\right)^2}} = 1 + \frac{L' K^2 \omega^2}{C_0 \left(1 - \left(\frac{\omega}{\omega_0}\right)^2\right)}$$

This condition cannot be satisfied independently of the frequency in a mathematically 10 precise manner. However from the use of approximated formulae results a satisfying mean correspondence of the two sides of the Equation 9 for $K=0.32 C_0$. This shows also that the use of the Equation 9 in first approximation is allowable, as for $K=0.32 C_0$ the number neglected herein compared to 1 has for the important frequencies only a value in the range of 3×10^{-3} .

For showing this correspondence, in Fig. 4, 20 the calculated quotient of the two sides of the Equation 8 for $K=0.3 C_0$ and $K=0.325 C_0$ are represented as a function between the relation of frequencies $\frac{\omega}{\omega_0}$. The value 1 of the quo-

tients corresponds to a precise correspondence. 25

By the quotient is indicated according to its importance the degree of correspondence between the real portion of the changed impedance of the line and the constant ohmic 30

resistance $a = \sqrt{\frac{L_0}{C_0}}$ of the simulation. From Fig. 4 may be seen that the simulation is sufficiently precise. It may be brought still nearer to the practical requirements by making the condenser K adjustable within the limits 0.3—0.33 C_0 and in adjusting the same by means of the known criterions to obtain the most favourable value for a good simulation. 40 According to this

$$K = (0.3 \text{ to } 0.33) C_0$$

In exactly the same manner the values L_1 , C_1 and L' are obtained from the Equation 7. 45 After substituting for G_1 , G_2 , a , b and c the expressions indicated hereabove in the Equation 7 it follows

$$(10) \quad \frac{L_1 \omega}{1 - L_1 C_1 \omega^2} + L' \omega = \frac{R_0 \omega}{4 \omega_0} + \frac{\frac{L_0}{C_0} + \frac{R_0^2}{16} \left(\frac{\omega}{\omega_0} + \frac{\omega_0}{\omega}\right)^2}{\sqrt{1 - \left(\frac{\omega}{\omega_0}\right)^2}} \cdot K \omega.$$

50 If in this equation

$$L' = \frac{R_0}{4 \omega_0}$$

55 is substituted for L' and

$$\frac{R_0^2}{16} \left(\frac{\omega}{\omega_0} + \frac{\omega_0}{\omega}\right)^2$$

60 is neglected compared to $\frac{L_0}{C_0} K \omega$ for the same reasons as before, according to the Equation 10

$$65 \quad \frac{L_1 \omega}{1 - L_1 C_1 \omega^2} = \frac{\frac{L_0}{C_0} K \omega}{\sqrt{1 - \left(\frac{\omega}{\omega_0}\right)^2}}.$$

This equation requires that

$$70 \quad L_1 = L_0 \frac{K}{C_0}.$$

Further the equation

$$75 \quad 1 - L_1 C_1 \omega^2 = \sqrt{1 - \left(\frac{\omega}{\omega_0}\right)^2}$$

can be approximately satisfied by

$$80 \quad C_1 = (0.54 \text{ to } 0.6) \frac{1}{L_1 \omega_0^2}$$

Fig. 5 shows the quotient of the two sides of the Equation 10 when the values found for

L_1 , L' and C_1 are substituted. Also in this case the most favourable value may be determined by an appropriated adjustment of C_1 within the given limits. 85

A correspondence still more precise is obtained by the use of the network shown in Fig. 7, in which two oscillating circuits L_1 , C_1 and L_2 , C_2 are connected in series in lieu of the single oscillating circuit as shown in Fig. 3. Then

$$G_2 = \frac{L_1 \omega}{1 - L_1 C_1 \omega^2} + \frac{L_2 \omega}{1 - L_2 C_2 \omega^2} + L' \omega \quad 95$$

and for

$$L_1 = L_2 = \frac{1}{2} K \frac{L_0}{C_0} \quad \text{and} \quad L' = \frac{R_0}{4 \omega_0}$$

the Equation 7 requires 100

$$\frac{1}{1 - L_1 C_1 \omega^2} + \frac{1}{1 - L_2 C_2 \omega^2} \approx \frac{1}{\sqrt{1 - \left(\frac{\omega}{\omega_0}\right)^2}}$$

In developing this equation members of the third power may still be taken into consideration and the values 105

$$C_1 = \frac{0.854}{L_1 \omega_0^2}, \quad C_2 = \frac{0.146}{L_2 \omega_0^2} \quad 110$$

are obtained.

Fig. 6 shows the precision obtainable in this way.

What I claim is:

1. A network for combining with a long 115

distance periodically loaded line to give to said combination an impedance substantially equal within the range of transmitted frequencies to the characteristic impedance of 5 a homogeneous line, said network comprising a capacity of value, K , of the order of 0.3 to 0.325 C_0 in shunt to said line, an inductance of value

$$\frac{R_0\sqrt{L_0C_0}}{8}$$

10 and a parallel resonant circuit, said inductance and said parallel resonant circuit being connected in series with each other and 15 with the line, L_0 , C_0 and R_0 being the total values of inductance, capacity, and resistance, respectively, per loading section of said line.

20 2. A network for combining with a long distance periodically loaded line to give to 25 said combination an impedance substantially equal within the range of transmitted frequencies to the characteristic impedance of a homogeneous line, said network comprising a capacity of value, K , of the order of 0.3 to 0.325 C_0 in shunt to said line, an inductance of value

$$\frac{R_0\sqrt{L_0C_0}}{8}$$

a parallel resonant circuit comprising an inductance of value, L_1 , equal to

$$\frac{KL_0}{2C_0}$$

30 and a capacity of value, C_1 , equal to

$$\frac{0.854}{L_1\omega_0^2}$$

35 and a second parallel resonant circuit comprising an inductance of value L_1 and a capacity of value

$$\frac{0.146}{L_1\omega_0^2}$$

40 said inductance and said parallel resonant circuits being connected in series with each other and with the line, L_0 , C_0 and R_0 being the total values of inductance, capacity and 45 resistance, respectively, per loading section 50 of said line and ω_0 being the limited frequency of said line, being equal to

$$\sqrt{\frac{4}{L_0C_0}}$$

55 In testimony whereof I affix my signature.

KARL KÜPFMÜLLER.
